UNITED STATES PATENT OFFICE.

GEORGE K. SNOW, OF WATERTOWN, MASSACHUSETTS.

MACHINE FOR FOLDING AND PASTING PAPER.

Specification of Letters Patent No. 27,392, dated March 6, 1860.

To all whom it may concern:

Be it known that I, GEORGE K. SNOW, of Watertown, in the county of Middlesex and State of Massachusetts, have invented a new and useful or Improved Machine for Folding and Pasting Paper; and I do hereby declare that the same is fully described and represented in the following specification and the accompanying drawings, of which—
10 Figure 1, denotes a top view. Fig. 2, a front elevation. Figs. 3, and 4, side elevations. Fig. 5, a rear elevation. Fig. 6, a longitudinal and vertical section. Fig. 7, a longitudinal and transverse section, and Fig. 15 8, a horizontal section of such machine. Fig. 9, is a vertical section taken through the sheet abutment and the packing trough to be hereinafter described.

So far as the folding of paper is concerned, the object I have had in view in the invention of my said machine, has been not only to fold a sheet of paper once but to make in it, one or more further parallel folds or turns in an opposite direction; that 25 is to say, if we suppose a sheet of paper to be folded with one fold or bend, *a*, as shown in end view in Fig. 10, *b*, *b*, being the parts of the sheet folded upon one another, my object has been to produce another fold in 30 either or both of the parts, *b*, *b*, and so that the paper shall be turned in an opposite direction, as represented in Fig. 11, wherein *c*, *c*, denote the bends or lines of folds; and furthermore the object I have had in view 35 has been also not only to so fold a sheet, but to further fold it in the same manner, at right or other angles with the folds so made. The first folding of the sheet, as shown in Fig. 11, causes it to present eight pages, or 40 four on a side; while when it is again folded, in the manner described, it will present either sixteen, twenty-four or thirty-two pages, according as it is folded either once, twice or three times. This double folding 45 of the sheet is new, and when carried out as described and represented, so as to cause the sheet to present twenty-four or thirty-two pages, it affords important advantages in binding the sheets.

50 I have also combined with a folding apparatus or mechanism, an apparatus or mechanism for applying paste or cement on such paper or parts of the sheet of paper as may be required, in order to cause the 55 sheet or parts of the sheet to adhere at any two or more of its folds or lines of fold:—

the same being for the purpose of either saving the usual process of either sewing or stitching together the folded parts of the sheet, or of connecting the folds, prior to 60 their being either sewed or stitched. And I have combined with such folding and pasting mechanism, a means of heating the pasted sheets for the purpose of drying the paste applied to them, and of causing the 65 parts of each sheet to adhere together at or near some of the lines of fold.

Figs. 12, and 13, exhibit the appearance of opposite sides of a thirty-two paged sheet with the lines of its folds. The colored 70 rectangular spaces are the imprinted pages, while the lines of fold are exhibited in red, and the lines of paste in blue. The number of each page is indicated therein by figures.

My machine, by removal of some one or 75 more of the side plates of the folding mechanism thereof, can be employed to fold a sheet with the double parallel foldings, so as to present either eight, sixteen or twenty-four pages; and in fact it may be arranged 80 so as to effect other numbers of pages.

In the drawings, *A*, denotes the frame of the machine, it being provided with a table or platform, *B*, upon which, a sheet to be folded is to be placed. This platform is 85 constructed with a long slit or opening, *d*, extending through it transversely. Projecting downward from opposite sides of said slit, are two sets of plates, *C*, *D*, *C'*, *D'*. Each of the said plates is supported by a 90 cross bar, *e*, and so that another or long thin plate, *E*, carried by a frame, *F*, may pass vertically upward and downward between each pair of plates, *C*, *D*, or *C'*, *D'*. Furthermore there is another pair of plates, 95 *G*, *H*, which, when at their highest elevation, extend above the platform, *B*, and are arranged with respect to it, and the other plates, as shown in the drawings. The two plates, *G*, *H*, are arranged a short distance 100 from one another, and on opposite sides of a bar, or arm, *I*, to which they are fastened; said bar being made to project horizontally from a frame, *K*, that plays vertically between two long posts or guides, 105 *L*, *L'*, arranged within and supported by the frame, *A*, and made to project above the table, *B*, as shown in the drawings. The frame *F*, carries the plate, *E*, and also projects from a sliding frame, *M*, that plays 110 vertically between the two posts or guides, *L*, *L'*, the same being arranged as shown in

the drawings. Again there is placed beneath the platform, B, and so as to stand at right angles to the two sets of plates, C, D, C', D', two other plates, N, O, they being 5 placed at a short distance asunder, and fastened at or near their outer edges to a slider or vertical plate, P, extending at top and bottom into horizontal and parallel guide grooves, f, f. In connection with the two 10 plates, N, O, and arranged on the opposite sides of the stationary plates, C, C', D, D', there is another vertical plate, R, arranged so as to slide backward and forward horizontally, and pass into the space between 15 the two plates, N, O, these latter plates also being capable of sliding between the two sets, C, C', D, D', of stationary plates.

In rear of the set of plates, C', D', and at a short distance therefrom, there is 20 a box or spout, S, it being arranged as shown in the drawings. One of the upright sides of the spout may be so applied to the bottom of such spout, as to be adjustable with reference to or be capable of being 25 moved either toward or away from, the other side of the spout, in order to adapt the spout to the width of the folded sheet that may be received into it. Against the outer side of the said box or spout, a box T, is arranged. 30 This box is intended to receive either steam or hot air, to be conveyed into it by a suitable conduit, leading either from a steam generator or air heating apparatus; the object being to apply heat to one side of the 35 spout for the purpose of heating it, and thereby heating such part of the pack of paper that may be within the spout, and against its heated side. The said heating apparatus I employ when folded sheets have 40 been pasted, prior to, or while being folded.

In connection with the folding apparatus, and the spout, S, I use in the machine a vertical abutment or plate, U, arranged as 45 shown in the drawings, and fastened to a sliding carriage or plate, V, sustained between parallel guides, g, g. Furthermore, between the said abutment and the receiving spout S, I employ a mechanism or frame for receiving each sheet of paper from the abutment, and conveying or pressing it back 50 upon the pack. This mechanism consists of a frame W, so applied to the inner end of the sheet spout, S, as to be capable of being moved both toward, and away from 55 the abutment U, so as to cause the abutment to enter the said frame. Fig. 14, shows a front view of the said frame, W, and exhibits the opening or mouth, k, for the 60 reception of the abutment. This opening is constructed rectangular, and a little less in depth than that of the folded sheet of paper; the same being in order that while the sheet is being forced through the said opening, both the upper and under edges of the sheet 65 may be bent a little, or the sheet be crowded

through the opening, so that after having passed through it, the said edges of the paper, by springing backward by their elastic power, and back of the bars, h, i, of the frame, may cause the frame to so hold the 70 paper, as to insure its being carried toward the pack, during and by the next retreat of the frame away from the abutment.

Fig. 15, is a top view, and Fig. 16, an inner side view of the frame W, as applied to the 75 sheet receiver or spout, S. From the said frame W, an arm or bar, i', extends, as shown in the said last two figures, and carries a projection or stud, k', that enters an inclined groove, X, carried by and formed in 80 the frame, F, the same being as shown in Fig. 9. As this groove is moved with and by the said frame, F, it will impart to the frame, W, its proper movements.

To the carriage, V, and the frame, A, a 85 hand lever, Z, is applied, so as to enable a person by taking hold of and moving the lever, to move the said carriage longitudinally, and cause the abutment 90 to be drawn backward. The object of so moving the abutment, U, is to enable an imperfectly folded sheet of paper, or an imperfect sheet, as the case may be, to be discharged from the machine, without being introduced into the trough, S. This will be caused by the 95 action of the sliding frame, W, which without the coöperation of the abutment, will not receive a sheet in manner as heretofore described, but while in movement will press the sheet over an opening, t, through which 100 it will drop and fall out of the machine. Therefore to cause the expulsion of a sheet, the attendant has only to move the hand lever so as to retract the abutment.

Having thus described the principal parts 105 of my invention by which the folding of a sheet of paper and its introduction into a packing trough are effected, I shall proceed to explain the mechanism for imparting motion to such parts.

In the drawings, m, denotes a driving or cam shaft, upon which are placed 3 grooved cams, n, o, p. The two cams, p, o, respectively receive in their grooves, projections from two levers, q, r, which play at their 115 rear ends, on a common fulcrum or pin, s, arranged at the rear part of the frame, A. The front end of one of the levers (r), is jointed to the sliding frame, F, and by means of a slot, t, formed in the lever, and made to receive an adjustable pin, u, applied to the frame so as to be capable of being raised or lowered therein, and fixed in any desirable position, such pin being shown in Fig. 20. The inner end of the other lever is jointed 120 to the lower end of an arm, v, extended downward from the sliding frame K. Figs. 17, 18 and 19, exhibit side views of the cams, n, o, p. The cam, n, receives within its groove, a projection or pin, w, extending 125 130

from an arm, a , that extends upward from a rocker shaft, y , arranged as shown in the drawings. From the said rocker shaft, a long arm, z , projects upward, and is formed 5 with a slot, a' , in its upper part as shown in Fig. 3, such slot being made to receive a stud, b' , extending from the plate R . This stud should be applied to the plate by means of devices which will enable the stud to be 10 adjusted horizontally, in a direction either toward or away from the front vertical edge of the plate. In Fig. 8, these devices are exhibited. They consist of a screw and nut applied to the plate or a slot therein, as 15 shown at c' , in such figure.

From the above it will be perceived that while the cam, n , is in rotation, it will cause motion to be imparted to the said plate, R . The connection plate, P , of the two plates, 20 N , O , has a stud, d' , projecting into a slot, u' , formed in the upper part of a lever, v' , arranged as shown in the drawings. The fulcrum, w' , of the said lever, is at the lower part of the lever, and just above the said fulcrum, a retractive spring, x' , is affixed to the lever and the frame, A , and serves to pull the former backward. Furthermore a latch, 25 y' , is jointed to the side of the arm, z , and takes upon a pin, z' , extending from the lever, v' . Under the said pin, z' , a bent tripping arm a^2 , projects from the lever, v' , in order to throw the catch of the latch off the pin, z' , at the proper time.

On the top surface of the platform, B , a 30 set of adjustable stops, b^2 , c^2 , d^2 , are arranged as shown in Fig. 1, each of the said stops consisting of a strip or plate of metal bent upward at or near its inner end. That portion of the plate which rests upon the platform, 35 is pressed underneath a holding strip of metal, e^2 , which is fastened at its two ends to the platform. Furthermore, the platform is provided with adjustable points, f^2 , f^2 , to extend above its surface and receive the paper like the points of a common printing press. Along in rear of the said points, is a 40 lifter bar, g^2 , which turns on fulcras, h^2 , h^2 , arranged as shown in Figs. 3 and 4, and is made to extend from an adjustable slider, i^2 , applied to the platform so as to be movable 45 either toward or away from the points. A slider, k^2 , arranged underneath the platform, carries a projection or cam, l^2 , applied to it, so as to be adjustable longitudinally of the machine. A cam, m^2 , carried by the sliding frame, M , is brought into contact with the inner end of the slider, k^2 , during the elevation 55 of the said frame, M , and moves the slider backward, so as to cause the lifter bar, g^2 , to be pressed upward against the sheet of paper in a manner to throw it off the points, and keep it off the same until it is drawn entirely away from them, which, having taken 60 place, a spring, n^2 , forces the slider, k^2 , forward, so as to drop the lifter bar down to a

horizontal position. Between the upper pair of plates G , H , and just beneath the bar or arm, I , to which they are attached, there is a bar, o^2 , that extends horizontally between the plates, and is made adjustable vertically, by 70 means of a screw, p^2 . A similar bar, q^2 , is applied between the two plates, N , O , and stands vertically and has an adjusting screw, r^2 , by which it may be moved toward and away from the connection plate, P . The object of each of the adjustable bars, o^2 , q^2 , is to serve as a stop, and to gage the distance 75 for the plate, E , or the plate, R , to work between its fellow plates G , H , or N , O .

The apparatus for applying the paste to a line or part of the sheet, at or near which the sheet is to be folded, may be thus described. A long roller, s^2 , revolves in a stationary trough, t^2 , and has a pinion gear, u^2 , fixed upon its shaft, v^2 . This pinion engages with a rack, w^2 , carried by the sliding frame, K , the vertical movements of such frame serving to produce the rotation of the fountain roller. Against the said fountain roller s^2 , a small pasting wheel, y^2 , bears, 90 such wheel being carried by an arm, a^3 , extending upward from a rocker shaft, b^3 , which is arranged as shown in the drawings. From the said rocker shaft, an arm, c^3 , extends inward, such arm, during the elevation 95 of the sliding frame, M , being struck by a projection or cam, f^3 , and elevated in such manner as to cause the pasting wheel to be moved downward upon the sheet of paper, and maintained there while such paper is 100 being drawn in to the space between the plates, G , and H . Afterward a spring, g^3 , serves to turn the shaft, b^3 , and elevate the pasting wheel up to the fountain roller, s^2 .

In order to keep from contact with the 105 plates, G , H , the paste that may be laid on a sheet of paper by the pasting wheel, I apply to each of such plates, a slotted plate or bearer, h^3 , and so that the parts on each side of the slot, i^3 , thereof, may project from the 110 plate, a sufficient distance to keep the line of paste on the paper, from adhering to the plate, G , or H . The slotted bearer may be applied to its plate or plates, so as to be adjustable thereon. An equivalent for such 115 bearer would be a vertical slot in each plate, G , or H ; but as this could not be made adjustable so conveniently as the separate slotted bearer, I prefer the latter. The slot in the folding plate would however have the 120 advantage of enabling the line or belt of paste to come more or less in contact with a portion of that part of the sheet which would be between the plates, G , H .

Fig. 20 is a vertical section taken through 125 the arm, c^3 , the same being made to show the two carriages or sliding frames M , and K , and their accessories. Figs. 21 and 22, are separate elevations of such frames.

There is a movable plate, p^3 , within the 130

packing box or spout, S; such plate being arranged vertically therein, and applied to springs, q^3 , q^3 , which extend from it, and bear against the sides of the spout, S. The 5 pack of folded paper rests against the said plate p^3 , and crowds it back, as fast as the said pack may increase in size; the object of the plate being to give support to the pack.

10 The above constitutes the description of the various parts of my said machine, whose mode of operation may be thus explained. Preparatory to applying a sheet of paper upon the platform, B, the machine is to be 15 put in movement so as to elevate the folding plates, G, H, to their highest position above the platform. This having been done, a sheet of paper is to be passed underneath the lower edges of the said folding plates, 20 and be properly adjusted on the platform by means of the points. We will suppose the middle of the sheet to be directly underneath the space between these two plates. Under this state of things, the plates, G, H, 25 are next made to descend a short distance until their lower edges may touch or nearly touch the sheet. In the mean time, the plate, E, will be raised upward to the sheet, and afterward, will be elevated further, so as 30 to press the sheet up between the two plates, G, H, and double it over. Half of the sheet will then be between the plates, while the remainder of the sheet will rest on the platform. Next the plates, G, H, and E, de- 35 scend together, so as to draw the sheet down entirely through and below the opening, d . This process will cause the sheet to be doubled back with two further folds or lines of fold, which will be parallel to the first 40 fold, or line of fold. Next the plate, E, not only descends further and entirely out of the sheet, but the plates, G, H, will be elevated again to their highest position, all of which will cause the sheet to remain between 45 the two pairs of plates, C, D, C', D', provided their inner surfaces hold to the sheet with sufficient friction, for which purpose, they should be covered wholly or partially with cloth or some elastic material or be 50 otherwise properly prepared to retain the sheet between them, during the movements of the plates, G, H, and E, away from it. Next the plate, R, will be driven forward 55 against the middle of the sheet, so as to force the sheet between the two plates, N, O, and draw it partly from between the plates, C, D, C', D'. Next the three plates, R, N, O, will be moved together in the opposite direction, so as to draw the sheet entirely out of 60 the spaces between the plates, C, D, C', D'. This, in connection with the inner edges of the plates C, D, C', D', will form the two outside folds of the sheet, the last three folds so made, having been formed at right angles 65 with the three first formed. Next the plates,

N, O, and R, recede, or are carried back to their normal positions, and leave the folded sheet of paper resting directly against the abutment U. Next the frame, W, is advanced toward the paper and the abutment, 70 and passes by the abutment, so as to cause the paper to be sprung into the mouth or opening of the said frame W, as hereinbefore described. Next the frame, W, re- 75 cedes, and forces the paper against the yielding plate, p^3 , or the pack of paper that may be against such plate. I would re- 80 mark that during the backward movement of the plate, R, the latch y' , will draw on the pin, z' , so as to move the lever, v' , and, 85 as a matter of course, move the plates, N, O. This will continue, until the arm, a^2 , may raise the latch off the pin, which taking place the spring, x' , will draw back the 90 said plates, N, O.

While the plates, G, H, are in the act of descending upon the middle of the sheet of paper, placed on the platform, B, the pasting wheel will be caused to leave the paste trough roller, and pass downward and rest 95 at its circumference upon the sheet, so that while the sheet is being forced up between the plates, G, H, it will be so drawn under the roller as to have a line or strip of paste applied to it by such roller. Subsequently 100 the pasting wheel will return to the fountain roller, for a fresh supply of paste.

A pasting apparatus of the above description, or its equivalent, should be applied to the platform, B, so as to operate above, over, 105 or through it, whenever it may be desirable to apply the paste to the sheet. Should it be required to apply the paste to the under- 110 side of the sheet, while resting on the plat- form, there should be a slot formed through the platform, to enable the paste wheel to work through it, and against the sheet. In general for folding a sheet into thirty-two 115 pages as shown in Figs. 12 and 13, the paste will be applied thereto, as indicated by the blue lines. This will cause the outside edge of one fold to adhere to the inside edge of that next to it. The lines or strips of paste however, may be so applied near the said 120 edges, as to cause the folds to adhere aside of such edges. Thus the sheet will not only be folded, but will be pasted so as to adhere together in or at some of its folds, or wherever it may be desired to have it connected. With my said machine printed sheets may be folded and their folds so connected, as to need no stitching to keep the leaves together, after the folded sheet may 125 have been trimmed.

My machine is calculated to produce the double folding in parallel lines of fold, so as to fold a sheet but twice in a manner to cause it to have six pages, which may afterward, by means of the plates, N, O, R, be 130 folded at right angles, either with two or

three parallel folds. It will be obvious to mechanicians that such machine can also perform various other foldings of a sheet of paper.

5. I do not herein claim a combination, consisting of mechanism for folding a sheet of paper once, and mechanism for folding it again at a right angle with the line of the first fold, but

10. I claim as my invention—

1. A machine or combination, consisting not only of mechanism for producing a single folding of a sheet of paper, but mechanism which shall operate to produce either 15 one or two further and parallel folds or turns of such paper in an opposite direction, substantially as specified; such mechanism, as shown in the drawings, being the plates G, H, C, D, and E, arranged and made to operate together, essentially in manner and by 20 means as hereinbefore set forth.

2. And I also claim a combination consisting not only of mechanism for folding a sheet of paper once, and mechanism for producing one or more further parallel folds or turns of the sheet in an opposite direction, but mechanism which shall operate to produce either one, two, or three folds of the sheet, at a right or other angle with the line 30 or lines of previous foldings of it, such combination of mechanism as exhibited in the drawings, being the plates, G, H, C, D, C', D', E, N, O, and R, operated in manner and by means substantially as heretofore described.

3. I also claim a combination or machine, consisting not only of mechanism for folding a sheet of paper one or more times, but mechanism for applying paste or cement on 40 such part or parts of the sheet as may be required in order to cause the sheet to stick together at any two or more of its folds or lines of fold; the mechanism shown in the drawings for applying paste, being the paste 45 roller, s^2 , paste fountain, t^2 , and the wheel, y^2 , arranged and operated relatively to the platform, B, and the folding plates, substantially as explained.

4. And in combination with the receiving trough or spout S, and the sheet abutment, 50 U, I claim the mechanism or frame, W, for receiving the sheet from the abutment, and conveying it toward, and pressing it upon either the pack or pack holder that may be within the trough, S.

5. And in connection with the receiving and conveying apparatus or frame, W, applied to the trough, S, and its abutment, U, as described, I claim the application to the abutment of a carriage, V, and a hand lever, 60 Z, or any equivalent mechanism by which such abutment may be moved in a direction away from the sheet receiver, so as to enable the latter to expel from the machine, an imperfect sheet, or an imperfectly folded sheet, 65 essentially as specified.

6. I also claim the arrangement and combination, in the manner described, of the adjustable stop bar, o^2 , with the two folding plates, G, H, and the plate, E, to run between them.

7. I also claim in combination with a paper folding machine, constructed so as to fold paper, or fold and apply paste to it, substantially as described, a heating apparatus, so applied as to heat a pack of folded paper while in the machine, the same being to facilitate the desiccation of the pack, or paste applied thereto, for the purpose set forth.

8. I also claim in a paper folding machine, the combination of the lifter bar, g^2 , with the register points, f^2 , applied to the platform upon which the sheet to be folded is to be placed.

9. I also claim the combination of the slotted plate or bearer, h^3 , or its equivalent, with a folding plate and a pasting apparatus of the paper folding machine, the same being to prevent the pasted part of a sheet of 90 paper from adhering to the outer surface of the folding plate.
